PERIODIC WAVE GENERATOR

John C. Wilson, Bayside, N. Y., assignor to Hazelton Corporation, a corporation of Delaware

Application August 26, 1938, Serial No. 226,874

8 Claims. (Cl. 250—36)

This invention relates to periodic wave generators and, while the invention is of general application, the generator of the invention is particularly suitable for deriving from a given wave 5 a wave of submultiple frequency for use as a timing wave in a television signal transmitter.

In generating timing pulses in a modulated-carrier television signal transmitter, some of 10 which form components of the transmitted signals, it is customary to generate high-frequency waves which are stabilized with respect to the source of alternating current at the transmitter and to derive therefrom waves of submultiple frequencies. The submultiple-frequency waves so 15 developed are used for the various timing operations necessary to generate and transmit the composite television signal. For example, in developing and transmitting a television signal involving double interlaced scanning and 441 lines 20 per second, it is customary to develop a high-frequency wave, for example, 26,460 cycles, which is stabilized with respect to a source of 60 cycle power supplying the transmitter. From this high-frequency wave there is derived a submultiple-frequency wave of 13,230 cycles, that is, half 25 the frequency of the high-frequency wave, which is utilized to produce line-frequency synchronizing pulses for the transmitted signal. By a further series of subdivisions, a 60 cycle wave is developed and utilized to provide field-frequency 30 pulses for the transmitted signal. A high degree of accuracy is essential in the relation between the frequencies of the different wave generators which go to make up the timer chain of the system. For this reason it is customary to develop 35 the waves in the manner described above rather than to generate waves of increasingly higher frequencies from the low-frequency source supplying the transmitter.

40 However, in subdividing a generated high-frequency wave to derive the waves of lower frequency, it is difficult to secure generators or frequency dividers for each of the steps which are not subject to some inaccuracies. If a particular 45 wave generator of lower frequency is to produce pulses of a frequency of $1/n$ times that of a higher frequency control wave, it is customary to provide a control circuit for the generator 50 which is responsive to pulses in the control wave which are separated by $n-1$ pulses. The usual way of accomplishing this is to provide a relaxation oscillator including a vacuum tube having a control electrode to which the desired pulses 55 are supplied. One particular circuit which has

been utilized comprises a condenser which is alternately charged from a direct current source and discharged, one of the operations being controlled by a vacuum tube. In this type of circuit the active period of the tube depends not only on 5 the control wave, usually applied to the control grid, but also upon the voltage of the condenser which is effectively coupled into the anode circuit of the tube and thereby affects its anode voltage. In previous circuits of this type, the 10 condenser is charged relatively slowly, either linearly or exponentially, and discharged rapidly, or vice versa. As a result, the anode voltage rises to a substantial value during the initial portion 15 of the linear or exponential charge or discharge and the slope of the anode voltage wave during the final portion of this period is of relatively low value so that the control tube may be controlled by a wrong pulse in the controlling wave or by some extraneous influence, such as static. 20 That is, the system is much too sensitive to controlling effects on its control electrode over substantially all of the linear or exponential charging or discharging periods.

It is an object of the invention to provide a 25 periodic wave generator which is not subject to the above-mentioned disadvantages.

It is a further object of the invention to provide a periodic wave generator which is very insensitive to a control wave, except during portions of each cycle when the control wave should be effective.

It is a further object of the invention to provide a periodic wave generator which is very insensitive with respect to any external influence, 35 except during a small portion of each cycle within which it is desired externally to influence the generator.

In accordance with the invention, a periodic wave generator adapted to be excited or fired by 40 selected pulses of a periodic-pulse wave which may include disturbing spurious pulses, comprises a capacitance means having charging and discharging circuits, the voltage across the capacitance means comprising the desired voltage 45 wave. Means are provided dependent at least in part upon the voltage of the capacitance means for controlling the charging and discharging circuits periodically and alternately to charge and discharge the capacitance means. The generator 50 also includes means for decreasing materially the susceptibility to firing by undesired pulses occurring between the selected pulses comprising impedance means included in one of the charging or discharging circuits, the impedance of the im-

pedance means being so proportioned with respect to the impedance constants of said one circuit that the slope of the voltage-time characteristic of the capacitance means during the greater portion of the final half of the active period of said one circuit is substantially greater than that of a linear voltage-time characteristic between the same charging voltage limits of the capacitance means.

10 In a preferred embodiment of the invention, a direct current circuit is provided for charging a condenser having the above-mentioned impedance means in circuit therewith and the control tube is utilized to discharge the condenser. The 15 control tube is provided with a control electrode to which may be applied control pulses. In this preferred embodiment, therefore, the impedance means prevents the voltage across the condenser from rising to the critical value, that is, above the 20 value it must have before the tube can be controlled by the pulses on the control grid, until such time as it is desired to control the tube. The circuit is thus very insensitive over nearly all of its charging cycle.

25 The novel features which are believed to be characteristic of this invention are set forth with particularity in the appended claims. The invention itself, however, both as to its organization and method of operation, together with further 30 objects and advantages thereof, will best be understood by reference to the following description taken in connection with the accompanying drawing, and its scope will be pointed out in the appended claims.

35 Fig. 1 is a simplified circuit diagram of a periodic wave generator embodying the invention; Fig. 2 illustrates the voltage time characteristics of a circuit similar to that of Fig. 1, if the charging circuit of the invention is not utilized; 40 Fig. 3 illustrates the characteristics of the circuit of Fig. 1 having constants proportioned in accordance with the invention; Fig. 4 is a circuit diagram of a further embodiment of the invention; Fig. 5 illustrates certain operating characteristics of the circuit of Fig. 4; and Fig. 6 is a 45 circuit diagram of a periodic-wave generator similar to that of Fig. 1 but comprising a high vacuum tube provided with regenerating means.

Referring now more particularly to the drawing, in Fig. 1 there is shown a periodic wave generator comprising a capacitance means 10 which is charged from a battery 11 through a circuit comprising a resistor 12 and an inductance 13. The discharging circuit comprises a vacuum tube 14, preferably of the vapor electric discharge type, having output electrodes connected across condenser 10 and having its control grid normally biased to cutoff by means of a source of voltage, indicated as $-C$, applied through a resistor 15.

50 Neglecting for the present the features of the circuit of Fig. 1 constituting the present invention, the wave generator described is similar to those which have previously been used and its operation is well understood in the art. Briefly, however, condenser 10 is charged exponentially from battery 11 during the period t_1 , t_2 (see Fig. 2) and is discharged by vacuum tube 14 during the time t_2 , t_3 , this cycle being indefinitely repeated. The periodic voltage across the condenser 10 may be utilized directly as, or may be utilized to derive, a secondary wave of a desired frequency. The wave A of Fig. 2 indicates a source of high-frequency pulses which may be 55 applied to the control electrode of electron dis-

charge device 14, each of the pulses being sufficient to bias the tube above its cutoff value during the pulse interval. When the vapor electric discharge tube 14 is so biased, its characteristic is such that if its anode voltage is above the value 5 V_c , Fig. 2, the tube may be rendered conductive by a pulse of the grid-voltage so that condenser 10 is rapidly discharged. Thus, tube 14 included in the discharge circuit of the capacitance means 10 is jointly controlled in accordance with the voltage of the capacitance means and predetermined pulses of the wave A applied to its control electrode, and the tube, therefore, comprises means dependent at least in part upon the voltage of the capacitance means for controlling the charging 10 and discharging circuits periodically and alternately to charge and discharge the capacitance means. Curve B of Fig. 2 indicates the voltage-time characteristic during the charging period of condenser 10 and it is seen that, at the time t_4 , 20 the condenser voltage and, therefore, the anode voltage of tube 14 rises above the critical value V_c and the tube may, therefore, be made conductive by pulse C, whereas it is desired that the generator should be insensitive to pulse C and should 25 be controlled by pulse D. Furthermore, due to the relatively large voltage applied to the anode of tube 14 during times in the vicinity of pulse C, extraneous influences, such as static pulses, may 30 easily cause tube 14 to become conductive even though pulse C itself did not have this effect.

In accordance with the present invention, inductance element 13 is inserted in the charging circuit of condenser 10 and its impedance and that of the resistor 12 are so proportioned relative to the impedance constants of the charging circuit comprised in large part by condenser 10 as to modify the time-voltage characteristic from that of curve B of Fig. 2 to that of curve B', shown in Fig. 3. The high-frequency wave A of 40 Fig. 3 is identical with that of Fig. 2. It is seen that the amplitude of the voltage time characteristic B' of condenser 10 at any predetermined time during its active or charging period is substantially less than that of characteristic B at a 45 corresponding instant of time over substantially all of the active period. Consequently, the amplitude of the voltage appearing across the capacitance means 10 at any predetermined time during the greater portion of the final half of the 50 active period of the charging circuit is substantially less than that resulting from a linear voltage-time characteristic between the same charging voltage limits of the capacitance means. Therefore, during such period, the voltage of the 55 condenser 10 does not rise dangerously close to the critical voltage V_c and the generator is not likely to be affected by extraneous pulses or transients occurring during this portion of the cycle. Further, it is seen from Fig. 3 that condenser 10 is charged at a rate much greater than the equivalent linear curve a , b over the greater portion of the final half t_5 — t_2 of its active period; that is, the slope of the voltage-time characteristic B' over the greater portion of the final half t_5 — t_2 60 of the charging or active period t_1 — t_2 is much greater than that of a linear voltage-time characteristic a , b between the same charging voltage limits V_2 — V_1 of condenser 10. It is thus evident that the amplitude of the voltage appearing 65 across the condenser 10 at any predetermined time during the greater portion of the final half of the charging period t_1 — t_2 is substantially less than that of a linear voltage-time characteristic between the same charging voltage limits V_1 — V_2 70

of the condenser. Therefore, the tube 14 is not responsive to the premature pulse C but only to the desired pulse D and is less likely to be tripped by extraneous transients occurring in time in the vicinity of pulse C. Thus, the system includes means for decreasing materially the susceptibility to firing by undesired pulses C occurring between the selected pulses D comprising impedance means 13, or means including the series-connected inductance element 13 and resistor 12, included in one of the charging and discharging circuits and proportioned as described.

One set of values for the circuit constants of Fig. 1 are as follows:

15	Tube 14	Type 884
	Capacitance 10	microfarad 0.05
	Battery 11	volts 170
	Resistance 12	ohms 5,000
20	Inductance 13	henries 20
	Normal operating frequency	cycles 60

The circuit of Fig. 4 differs from that of Fig. 1 primarily in the fact that a vacuum tube 20 has been provided for effectively opening or interrupting the charging circuit of condenser 10 during the interval when condenser 10 is being discharged through tube 14. Similar circuit elements have been given similar reference numerals in the two figures. The output electrodes of vacuum tube 20 are connected directly in the charging circuit comprising series-connected inductance 13 and resistor 12, while a resistor 21 is included in the discharge circuit of condenser 10 and in the input circuit of tube 20.

In considering the operation of the circuit of Fig. 4, it will be seen that, when tube 14 becomes conductive to discharge condenser 10, an appreciable voltage is developed across resistor 21 by the discharge current which voltage is applied to the control electrode of vacuum tube 20, thereby to bias the same beyond its cutoff value and effectively open the charging circuit of the system. The characteristics of the wave generator of Fig. 4 are illustrated in Fig. 5 from which it is seen that, by opening the charging circuit of the condenser 10 while the condenser is being discharged, the amplitude of the condenser voltage is further decreased during the initial portion of the charging period and the slope of the charging voltage time curve of condenser 10 is further increased during the final portion of the charging period. This is shown by curve B'' of Fig. 5. From this curve, it is seen that the amplitude of the voltage across the condenser 10 at any predetermined time during the final half $t_5 - t_2$ of the charging period $t_1 - t_2$ is even less than that resulting from the voltage-time characteristic of the Fig. 1 arrangement, as indicated by the curve of Fig. 3, and especially is this so during the relatively short interval $t_5 - t_2$ which immediately precedes the desired synchronizing pulse D. Therefore, the circuit of Fig. 4 is much less sensitive over the initial portion of the charging period than the circuit of Fig. 1 and is at least equally sensitive to the desired synchronizing pulses near the end of the charging period. Thus, resistor 21 comprises impedance means in circuit with vacuum tube 20 for controlling the periods of conductivity of this tube.

70 One set of values for the circuit of Fig. 4 preferably are as follows:

Tube 14	Type 884
Tube 20	Type 6C5
75 Resistance 21	Between 100 and 500 ohms

The other values remain the same as those given above for Fig. 1.

While there has been described a periodic wave generator comprising a vapor electric discharge tube for discharging the condenser, it will be understood that the principles of the invention are equally applicable to an arrangement, as shown by Fig. 6, utilizing a high vacuum tube 18 including suitable regenerating means, comprising inductively coupled windings 17, 18, to change the conductivity of the tube from minimum to maximum for a small difference in grid voltage such as that of Fig. 1 of Patent 2,148,096, issued February 12, 1939, to G. B. Banks. Further, the vacuum tube may be included in the charging circuit of the condenser rather than the discharging circuit, as shown by Patent 2,118,352, dated May 24, 1938, in which case the discharge circuit is proportioned in accordance with the above principles.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A periodic wave generator adapted to be fired by selected pulses of a periodic-pulse wave which may include disturbing spurious pulses, comprising capacitance means, charging and discharging circuits for said capacitance means, means dependent at least in part upon the voltage of said capacitance means for controlling said circuits periodically and alternately to charge and discharge said capacitance means, and means for decreasing materially the susceptibility to firing by undesired pulses occurring between said selected pulses comprising impedance means included in one of said circuits, the impedance of said impedance means being so proportioned with respect to the impedance constants of said one of said circuits that the slope of the voltage-time characteristic of said capacitance means during the greater portion of the final half of the active period of said one of said circuits is substantially greater than that of a linear voltage-time characteristic between the same charging voltage limits of said capacitance means.

2. A periodic wave generator adapted to be fired by selected pulses of a periodic-pulse wave which may include disturbing spurious pulses, comprising capacitance means, charging and discharging circuits for said capacitance means, means dependent at least in part upon the voltage of said capacitance means for controlling said circuits periodically and alternately to charge and discharge said capacitance means, and means for decreasing materially the susceptibility to firing by undesired pulses occurring between said selected pulses comprising impedance means included in one of said circuits, said impedance means being so proportioned with respect to the reactive constants of said one of said circuits that the amplitude of the voltage appearing across said capacitance means at any predetermined time during the greater portion of the final half of the active period of said one of said circuits is substantially less than that resulting from a linear voltage-time characteristic between the same charging voltage limits of said capacitance means.

3. A periodic wave generator adapted to be fired

- by selected pulses of a periodic-pulse wave which may include disturbing spurious pulses, comprising capacitance means, charging and discharging circuits for said capacitance means, means dependent at least in part upon the voltage of said capacitance means for controlling said circuits periodically and alternately to charge and discharge said capacitance means, and means for decreasing materially the susceptibility to firing by undesired pulses occurring between said selected pulses comprising means including a series-connected inductance and resistor in one of said circuits, the values of said inductance and said resistor being so proportioned with respect to the value of said capacitance means that the amplitude of the voltage appearing across said capacitance means at any predetermined time during the greater portion of the final half of the active period of said one of said circuits is substantially less than that resulting from a linear voltage-time characteristic between the same charging voltage limits of said capacitance means.
4. A periodic wave generator adapted to be fired by selected pulses of a periodic-pulse wave which may include disturbing spurious pulses, comprising capacitance means, charging and discharging circuits for said capacitance means, means comprising a vacuum tube included in one of said circuits controlled at least in part in accordance with the voltage of said capacitance means for controlling said circuits periodically and alternately to charge and discharge said capacitance means, and means for decreasing materially the susceptibility to firing by undesired pulses occurring between said selected pulses comprising impedance means included in the other of said circuits, said impedance means being so proportioned with respect to said capacitance means that the amplitude of the voltage appearing across said capacitance means at any predetermined time during the greater portion of the final half of the active period of said one of said circuits is substantially less than that resulting from a linear voltage-time characteristic between the same charging voltage limits of said capacitance means.
5. A periodic wave generator adapted to be fired by selected pulses of a periodic-pulse wave which may include disturbing spurious pulses, comprising capacitance means, charging and discharging circuits for said capacitance means, means dependent at least in part upon the voltage of said capacitance means for controlling said circuits periodically and alternately to charge and discharge said capacitance means, and means for decreasing materially the susceptibility to firing by undesired pulses occurring between said selected pulses comprising impedance means included in one of said circuits, said impedance means being so proportioned with respect to said capacitance means that the amplitude of the voltage appearing across said capacitance means at any predetermined time during the greater portion of the final half of the active period of said one of said circuits is substantially less than that resulting from a linear voltage-time characteristic between the same charging voltage limits of said capacitance means, and means for effectively disconnecting said one of said circuits from said capacitance means during its inactive period to decrease further the amplitude of the voltage appearing across said capacitance means during the greater portion of the final half of said active period.
6. A periodic wave generator adapted to be

fired by selected pulses of a periodic-pulse wave which may include disturbing spurious pulses, comprising capacitance means, a charging circuit for said capacitance means, means comprising a vacuum tube controlled in accordance with the voltage across said capacitance means for discharging said capacitance means at periodic intervals, and means for decreasing materially the susceptibility to firing by undesired pulses occurring between said selected pulses comprising impedance means included in said charging circuit, said impedance means being so proportioned with respect to the impedance constants of said charging circuit that the amplitude of the voltage appearing across said capacitance means at any predetermined time during the greater portion of the final half of the charging period of said capacitance means is substantially less than that resulting from a linear voltage-time characteristic between the same charging voltage limits of said capacitance means, and means including a vacuum tube included in said charging circuit for effectively interrupting said charging circuit during the discharge period of said capacitance means to decrease further the amplitude of the voltage appearing across said capacitance means during the said greater portion of the final half of said active period.

7. A periodic wave generator adapted to be fired by selected pulses of a periodic-pulse wave which may include disturbing spurious pulses, comprising capacitance means, a charging circuit for said capacitance means, means comprising a vacuum tube controlled in accordance with the voltage across said capacitance means for discharging said capacitance means at periodic intervals, and means for decreasing materially the susceptibility to firing by undesired pulses occurring between said selected pulses comprising impedance means included in said charging circuit, said impedance means being so proportioned with respect to the impedance constants of said charging circuits that the amplitude of the voltage appearing across said capacitance means at any predetermined time during the greater portion of the final half of the charging period of said capacitance means is substantially less than that resulting from a linear voltage-time characteristic between the same charging voltage limits of said capacitance means, a vacuum tube included in said charging circuit for effectively interrupting said charging circuit during the discharge period of said capacitance means to decrease further the amplitude of the voltage appearing across said capacitance means during the said greater portion of the final half of said active period, and means including impedance means in circuit with said first-mentioned vacuum tube for controlling periods of conductivity of said last-mentioned vacuum tube.

8. A periodic wave generator adapted to be synchronized by selected pulses of a periodic-pulse wave which may include disturbing spurious pulses, comprising capacitance means, charging and discharging circuits for said capacitance means, means comprising a vacuum tube having a control electrode for controlling said circuits periodically and alternately to charge and discharge said capacitance means, said last-mentioned means being controlled jointly in accordance with the voltage of said capacitance means and predetermined pulses of said wave applied to said control electrode, and means for decreasing materially the susceptibility to synchronization by undesired pulses occurring between said selected pulses.

lected pulses comprising impedance means included in one of said circuits, said impedance means being so proportioned with respect to said capacitance means that the amplitude of the voltage appearing across said capacitance means at any predetermined time during the greater por-

tion of the final half of the active period of said one of said circuits is substantially less than that resulting from a linear voltage-time characteristic between the same charging voltage limits of said capacitance means.

JOHN C. WILSON.
